CLAIM

The ornamental design for a box, as shown and described.

DESCRIPTION

FIG. 1 is a top perspective view of a box showing my new design.

FIG. 2 is a front view of a box.

FIG. 3 is a rear view of a box.

FIG. 4 is a left side view of a box.

FIG. 5 is a right side view of a box.

FIG. 6 is a top view of a box.

FIG. 7 is a bottom view of a box; and,

FIG. 8 is a top perspective exploded view thereof, showing the separated state.

The broken lines in the drawings depict portions of the box that form no part of the claimed design.

1 Claim, 8 Drawing Sheets
